(57) **CLAIM**

I claim, the ornamental design for a saw blade, as shown and described.

DESCRIPTION

FIG. 1 is a perspective view of a saw blade, showing my new design;

FIG. 2 is a side view thereof, the opposite side view being a mirror image thereof;

FIG. 3 is a top view thereof, the opposite bottom view being a mirror image thereof;

FIG. 4 is a top view thereof in another embodiment, the opposite bottom view being a mirror image thereof;

FIG. 5 is a top view thereof in another embodiment, the opposite bottom view being a mirror image thereof; and,

FIG. 6 is a top view thereof in another embodiment, the opposite bottom view being a mirror image thereof.

The broken lines show environment and form no part of the claimed design.
